UNITED STATES PATENT OFFICE.

ERNEST J. BRASSEUR, OF CHICAGO, ILLINOIS, ASSIGNOR TO A. B. DICK COMPANY, OF CHICAGO, ILLINOIS, A CORPORATION OF ILLINOIS.

INKING MEANS FOR DUPLICATING MACHINES.

Application filed January 31, 1925. Serial No. 5,945.

To all whom it may concern:

Be it known that I, ERNEST J. BRASSEUR, a citizen of the United States, residing in the city of Chicago, county of Cook, and State of Illinois, have invented certain new and useful Improvements in Inking Means for Duplicating Machines, of which the following is a specification.

This invention relates to duplicating machines, and more particularly to inking means therefor, etc.

Heretofore it has been customary to rely solely upon the natural permeation of ink through the inking pad of a duplicating machine, aided by the pressure placed on the outside of a pad during the printing operation, to bring the ink to the outside of a pad for transmission through the stencil to effect reproduction. I have discovered that there is quite an advantage in forcing the ink through the pad by additional means, such as by establishing air pressure behind the pad, since such pressure forces ink outwardly through the pad and replenishes the outer surface thereof adequately and very quickly.

Accordingly, one of the objects of my invention is to provide means for establishing air pressure on the rear of the inking pad after a general distribution of ink has been made on the rear surface thereof.

I have also discovered that a short application of air pressure on the rear of a pad which has become quite dry from non-use or from the congestion of ink thereon will restore the pad to usable condition. Accordingly, the object of my invention is also to provide means for reconditioning a pad which has become unsatisfactory for use on account of the drying out and congestion of old ink thereon.

A further object of my invention is to provide a simple, efficient and practical construction for establishing suitable pressure at the rear of the pad to force ink through the pad to replenish the outer surface thereof adequately and quickly.

Other objects of my invention will be in part obvious and in part pointed out hereinafter.

In carrying out my invention, I preferably provide means for establishing air pressure in a compartment constructed immediately behind the inking pad when carried on the machine. In my prior application Serial No. 726,465, filed July 17, 1924, for duplicat-

ing machines, and also in an application filed by me on even date herewith for duplicating machines, I have disclosed a sealed compartment immediately behind the inking pad, and means for making a general distribution of ink to the rear surface of this pad through a diaphragm over which the pad is placed. Any suitable means adapted to either manual or automatic operation may be associated with such compartment for establishing the desired air pressure therein, either continuously or intermittently, or only spasmodically as and when desired. The pressure-creating means may take the form of a suitable air pump.

In order that a clearer understanding of my invention may be had, attention is hereby directed to the accompanying drawings, forming a part of this application and illustration one certain embodiment of my invention.

Referring to the drawings:

Fig. 1 is a diagrammatical view of a duplicating machine such as disclosed in my said prior application Serial No. 726,465, showing one possible means of creating the desired air pressure associated therewith;

Fig. 2 is an enlarged end view of the air entrance port into the compartment; and

Fig. 3 is a sectional view of the same, and is taken on the line 3—3 of Fig. 2.

Similar reference characters refer to similar parts throughout the several views of the drawings.

Referring to the drawings, 1 indicates a suitable support upon which the drum 2 of the duplicating machine is mounted for rotation by means of suitable handle 3. The drum carries the diaphragm 4 and an inking pad 5. These elements 4 and 5 comprise a portion of a sealed compartment 6, which is constructed within the drum 2. This compartment has a side wall 7, and the drum 2 has an adjacent side wall 8. A nipple 9 extends through walls 7 and 8 and is held in place on wall 7 by means of an enlarged head 10 and a nut 10' screwed upon the nipple, the head 10 and nut 10' being on opposite sides of the wall 7. The head 10 carries a conical metallic member 11, which at its enlarged inner end has a plurality of radial finger portions 11', which extend through suitable perforations in the side wall of a cap member 12, the ends of fingers 11' being flanged over, as at 13, whereby the cap 12

is held in place. The cap 12 is inverted with respect to the member 10, so that air entering through the nipple 9 and member 10 will be deflected rearwardly by the cap 12 and spread within the compartment 6.

It will be evident that when air is forced through the nipple 9 by any suitable means, there will be air pressure built up within the compartment 6. This air pressure will 10 act through the diaphragm 4 against the inking pad 5 and will tend to force ink to the outer surface of the pad 5.

To create this air pressure, it has been found suitable to employ a simple hand air 15 pump 14 of conventional form. This pump may be connected with the end of the nipple 9, which extends outside of the wall 8 of the drum, by means of a suitable tube 15.

The operation is as follows: After a general 20 distribution of ink has been made to the diaphragm 4, pump 14 may be connected with the nipple 9 and operated until a satisfactory quantity of ink has been forced to the outside of the inking pad 5 due to the increased air pressure within compartment 6 resulting from working the pump. The pump then may be disconnected from the nipple 9 and the machine operated in the usual manner. If, at any time during the 25 operation of the machine, it is found that the outer surface of the inking pad 5 needs replenishment, this may be accomplished almost immediately by applying the pump and giving it a few strokes.

Should the inking pad 5 be unsuitable for use, due to drying or congestion of ink thereon, the pump 14 may again be used to build up air pressure within the compartment 6, whereby fresh ink will be forced to the outer 30 surface of the inking pad 5, and the pad will be reconditioned for use.

Heretofore the customary manner of replenishing the outer surface of the inking pad with ink has been to either distribute more ink on the interior of the pad or to lessen the speed of cylinder revolutions to give time for the ink to permeate through the pad and to accumulate on its outer surface. By means of my invention, neither 45 of these ways of replenishing the outer surface of the pad are necessary, since by the use of the pump the outer surface of the pad is replenished with ink almost immediately and also very evenly, and accordingly 50 it is possible to print more rapidly and with an assured abundance of ink.

Heretofore, when a pad has become quite dry from non-use or from ink congested thereon from long continued use, it has 55 been customary to replace the pad or to turn it over. Both of these undertakings are very objectionable and time-consuming.

The pads are, of course, covered with ink and it is a very dirty undertaking to handle them. This is now rendered unnecessary, since, as above pointed out, a few strokes of the pump will recondition such a pad.

Excessive air pressure cannot be created because the air above a certain pressure will find release automatically through the outer 60 edges of the pad.

As many changes could be made in the above construction and as many apparently widely different embodiments of my invention could be made without departing from the scope thereof, it is intended that all matter contained in the above description or shown in the accompanying drawings shall be interpreted as illustrative and not in a limiting sense.

I claim:—

1. In a device of the character described, in combination, an inking pad, and means for establishing air pressure behind said pad.

2. In a device of the character described, in combination, an inking pad, a compartment behind said pad, and means for establishing air pressure within said compartment and against said pad.

3. In a device of the character described, in combination, a drum of a stencil-duplicating machine, a sealed compartment within said drum, an inking pad comprising a portion of the walls of said compartment, and means for establishing air pressure within said compartment.

4. In a device of the character described, in combination, an inking pad adapted to receive ink on one surface thereof, and pneumatic means for forcing said ink through said pad and to the other surface thereof.

5. In a device of the character described, in combination, an inking pad, means whereby a general distribution of ink may be made to one side of said pad, and pneumatic means for forcing said ink through the pad on to the other surface thereof.

6. In a device of the character described, in combination, an inking pad, an air compartment behind said pad, and means including an air pump for establishing air pressure within said compartment and against said inking pad.

7. In a device of the character described, in combination, an inking pad, an air compartment behind said pad and in open communication therewith, an air inlet port into said compartment, and a pump for forcing air into said compartment through said inlet port.

This specification signed this 28th day of January, 1925.

ERNEST J. BRASSEUR.
